UNITED STATES PATENT OFFICE

96,202

DESIGN FOR A MACARONI

Angelo Ronzoni, New York, N. Y.

Application April 13, 1935, Serial No. 56,356

Term of patent 14 years

To all whom it may concern:

Be it known that I, Angelo Ronzoni, a citizen of the United States, residing at New York, in the county of Queens and State of New York, have invented a new, original, and ornamental Design for a Macaroni, of which the following is a specification, reference being had to the accompany drawing, forming part thereof.

Fig. 1 is a plan view of the macaroni.

Fig. 2 is an elevation taken along the line 2—2 of Fig. 1.

Fig. 3 is an elevation taken along the line 3—3 of Fig. 1, and

Fig. 4 is an elevation taken along the line 4—4 of Fig. 1.

I claim:

The ornamental design for a macaroni, as shown.

ANGELO RONZONI.
